Inventor

Allen J. Tingley
By William D. Deane
his Attorney

UNITED STATES PATENT OFFICE.

ALLEN J. TINGLEY, OF OWOSSO, MICHIGAN.

FENCE.

1,275,795.

Specification of Letters Patent. Patented Aug. 13, 1918.

Application filed April 19, 1917. Serial No. 163,121.

To all whom it may concern:

Be it known that I, ALLEN J. TINGLEY, citizen of the United States, residing at Owosso, in the county of Shiawassee and 5 State of Michigan, have invented certain new and useful Improvements in Fences, of which the following is a specification.

My present invention pertains to fences and analogous structures.

10 It has for its general object to provide a barricade or temporary fence for use in streets or roadways to guard excavations.

A further object of the invention is to 15 provide apparatus of the above mentioned character, adapted for use inside or outside of buildings or the like, to form inclosures.

A further object of the invention is to 20 provide apparatus of the above mentioned character, the parts of which may be assembled and separated in a highly convenient and expeditious manner.

A further object of the invention is to 25 provide apparatus of the above mentioned character, the parts of which are adapted to be arranged in a compact manner for shipment, and which parts may be readily handled by unskilled labor.

The invention also contemplates the 30 construction of the barricade or temporary fence in such manner that it is rigid and strong and is therefore well adapted to withstand pressure.

With the foregoing in mind the invention 35 will be fully understood from the following description and claims when the same are read in connection with the drawings.

In the accompanying drawings which are for illustrative purposes only, and therefore not drawn to any particular scale:

40 Figure 1 is a side elevation of a fence section or barricade constructed in accordance with my invention.

Fig. 2 is a transverse vertical sectional view on an enlarged scale taken on line 2—2 45 of Fig. 1.

Figs. 3, 4 and 5, respectively are horizontal sectional views taken on the lines 3—3, 4—4 and 5—5 of Fig. 2 respectively.

Fig. 6 is an end elevation of one of the 50 sections.

Fig. 7 is a fragmentary vertical section of the upper portion thereof.

Fig. 8 is a detailed perspective view of one of the uprights.

55 Fig. 9 is a detailed horizontal sectional

view showing a barricade arranged at right angles.

Fig. 10 is a fragmentary side elevation showing the manner in which the runners are lapped, when a series of them is employed.

In the illustrated embodiment of my invention the transverse supports or uprights are numbered 1, the lower and intermediate

runners, 2, and the crown bars or upper 60 runners, 3. The transverse supports 1 are identical in construction and therefore a detailed description of the one shown in Figs.

2 to 8 will suffice to impart a definite understanding of all. The transverse support referred to comprises upwardly converged timbers 4, the upper opposed portions of

which are mitered as indicated by 5. Short wooden bars 6 are disposed at opposite sides of the upper portions of the timbers 4 and 75 bolted thereto, as indicated by 7. An up-

right metallic member 8, of I-form in horizontal section is superimposed on the bars 6 and interposed between and receiving and held in position by the mitered portions of 80 the timbers 4. As is apparent from Fig. 5, the member 8 is provided upon its opposite sides with grooves 8', for receiving the mitered ends of the timbers 4. As clearly

shown in Fig. 7, the member 8 is provided 85 at its lower ends with stop lugs 9', which close the lower ends of the grooves 8', and engage beneath the mitered ends of the timbers 4. A head 9 is integral with or

otherwise fixed on the upper end of the 90 member 8 and has four horizontally-disposed ways or sockets 10. The head 9 extends laterally beyond the member 8, upon opposite sides thereof, and is disposed above and in contact with the upper ends of the

timbers 4. A clamping plate 11 is movable vertically between the walls of the head 9, with a screw 12 bearing in the upper wall 95 of the head 9 and swiveled at 13 to the plate 11. This screw has a suitable handle 14 at its upper end. An upright member 15, partly of

wood and partly of metal, has an upper portion arranged and held between the upper portions of the timbers 4 and also between the bars 6. A comparatively long wooden bar 16 is bolted at 17 to the timbers 4 and at 18 to the upright member 15. The wooden portion 100 of the upright member 15 is L-shaped in cross-section and is provided with two series of horizontally-disposed apertures;

105

110

115

120

one series 19 being disposed at right angles to the other series 20. The apertures of the series 20 are formed in the edge of the wooden portion and are closed by an upright metallic strip 21 which is permanently connected to the said wooden portion and serves the additional function of lending increased strength thereto.

In erecting a barricade or fence section embodying my invention, two transverse supports or uprights of the construction described are positioned a suitable distance apart and in parallel relation, and runners 2 are placed and supported in the apertures 20 of the upright members 15. The crown bar 3 is disposed at its ends in the ways or sockets 10 in the heads 9 of the transverse supports or uprights and are secured in said position by the clamping plates 11 and screws 12, with the result that the said transverse supports or uprights are strongly maintained in upright positions.

When the fence section or barricade comprises three of the transverse supports or uprights, the meeting portions of crown bars 3 in the ways or sockets 10 of the head 9 on the intermediate transverse support or upright may be and preferably are reduced and lapped in the said head 9 so as to be securely held by the clamping means complementary thereto, as shown at 3' (see more particularly Fig. 10.) Also in this arrangement the meeting portions of the runners 2 in the apertures 20 of the upright member comprised in the intermediate transverse support or upright are lapped. I would further have it understood at this point that in practice the runners and crown bars alluded to may be formed by "two by fours" or "two by eights" or each runner or crown bar may be formed by "one by fours" or "one by eights" doubled, and the barricade or fence may be made either "tight" or "open" in the discretion of the party practising the invention.

When it is desired that the barricade or fence comprise a section extending at right angles to the section described a transverse support or upright is arranged at a suitable distance from one of the transverse supports or uprights described and at right angles thereto. The runners are arranged in the apertures 20 of the last-named transverse support or upright and in the apertures 19 of the other transverse support or upright, while a crown bar is arranged in the proper apertures or sockets in the heads of the two transverse supports or uprights, as indicated in Fig. 7.

When it is desired to disassemble the parts of a barricade or fence constructed in accordance with my invention, the same manifestly may be quickly and easily accomplished, and when the runners and crown bars are removed from the transverse sup-

ports or uprights, the said transverse supports or uprights may be compactly arranged in a small space for storage or transportation. Indeed a large number of the transverse supports or uprights may be piled up in small compass and may be conveniently transported from place to place for use in combination with "two by fours" or other timbers such as are readily procurable in various localities.

I have entered into a detailed description of the construction and relative arrangement of the parts embraced in the present and preferred embodiment of my invention in order to impart a full, clear and exact understanding of the said embodiment. I do not desire, however, to be understood as confining myself to the said specific construction and relative arrangement of parts since in the future practice of my invention such changes or modifications may be made as fairly fall within the scope of my invention as claimed.

Having described my invention, what I claim and desire to secure by Letters Patent, is:

1. A support for use in a barricade, having a plurality of horizontally-disposed timber-receiving apertures at intervals in its height and extending in the same direction, a plurality of horizontally-disposed timber-receiving apertures at intervals in its height and extending at right angles to the first-named apertures, and means complementary to one of said apertures for securing a timber therein.

2. A support for use in a barricade, having a head in which are oppositely-extending horizontally-disposed apertures, and a device common to said apertures for securing a timber therein, and also having a plurality of horizontally-disposed timber-receiving apertures at intervals in its height and extending in the same direction, and a plurality of horizontally-disposed timber-receiving apertures at intervals in its height and extending at right angles to the second-named series of apertures.

3. A transverse support for use in a barricade, comprising upwardly converged timbers connected together and having mitered upper portions, an upright portion, of I-form in horizontal-section, interposed and supported between said mitered portions, an apertured head arranged on and fixed with respect to said portion, clamping means carried by said head and an upright member fixed between the upwardly converged timbers and having horizontally-disposed apertures.

4. A transverse support for use in a barricade, comprising upwardly converged timbers connected together and having mitered upper portions, an upright portion, of I-form in horizontal-section, interposed and

- supported between said mitered portions, an apertured head arranged on and fixed with respect to said portion, clamping means carried by said head and an upright member 5 fixed between the upwardly converged timbers and having portions disposed at right angles to each other in which are horizontally-disposed apertures for the reception of runners extending at right angles to each 10 other.
5. A transverse support for use in a barricade, comprising upwardly converged timbers connected together and having mitered upper portions, an upright portion, of I- 15 form in horizontal-section, interposed and supported between said mitered portions, an apertured head arranged on and fixed with respect to said portion, clamping means carried by said head and an upright member 20 fixed between the upwardly converged timbers and having portions disposed at right angles to each other in which are horizontally-disposed apertures for the reception of runners, the apertures in one portion being formed in the vertical edge thereof and the portion being provided on said edge with a metallic strip for closing said 25 apertures.
6. A transverse support for use in a barricade, comprising upwardly converged timbers having mitered upper portions, a lower horizontal bar extending between and connected to the lower portions of said timbers, upper horizontal bars arranged at opposite 30 sides of and connected to said timbers, an upright portion of I-form in horizontal-section, interposed and supported between said mitered portions, an apertured head arranged on and fixed with respect to said 35 portion, clamping means carried by said head, and an upright member fixed to the lower horizontal bar and arranged with its upper portion between the upper horizontal bars and the upper portions of the upwardly 40 converged timbers.
7. In a fence of the character described, upwardly converging timbers having their upper ends mitered; a member arranged between and having grooves receiving the 45 mitered ends of the timbers, with stop lugs in the lower ends of the grooves to engage beneath the mitered ends; a head rigidly secured to the upper end of the member and extending laterally upon opposite sides of 50 the same to contact with the tops of said mitered ends, said head having a bar receiving socket; means to rigidly connect the end portions of the timbers; and clamping 55 means operating within the socket.
8. In a fence of the character described, 60 upwardly converging timbers having their upper ends mitered; a member arranged between and having grooves receiving the mitered ends of the timbers, with stop lugs formed upon the lower end of the member 65 and disposed in the lower ends of the grooves to engage beneath the mitered ends; a head rigidly secured to the upper end of the member and extending laterally upon opposite sides of the same to contact with the tops of 70 said mitered ends, said head having a bar receiving socket; a clamping element disposed within the socket; and a screw having screw threaded engagement with the upper end of the head and connected with the 75 clamping element.
9. In a fence of the character described, 80 upwardly converging timbers, having their upper ends mitered; a member arranged between and having grooves receiving the mitered ends of the timbers; a pair of substantially horizontal strips disposed upon opposite sides of the upper end portions of the timbers in proximity to the member and secured to the timbers; a lower pair of substantially horizontal strips disposed upon opposite sides of the timbers and secured thereto; 85 an upright timber arranged between the upper and lower pairs of strips with its upper end contacting with the lower end of 90 said member, said upright timber having rail receiving openings and being secured to the lower pair of strips; a head rigidly secured to the upper end of the member and having a bar receiving socket; and clamping 95 means operating within the socket.
10. A support for use in a barricade, having a head in which are oppositely-extending horizontally-disposed apertures, and a device common to said apertures for securing a timber in the head. 100
11. A support for use in a barricade, comprising a head in which are oppositely-extending horizontally-disposed apertures, a device common to said apertures for securing a timber in the head, and an upright member disposed under the head and fixed with respect thereto; said upright member having portions disposed at right angles to each other and also having horizontally- 110 disposed apertures in said portions.

In testimony whereof I affix my signature in presence of two witnesses.

ALLEN J. TINGLEY.
